EYE MUSCLE EXERCISING APPARATUS

Phillip S. Newton, Oakland, Calif.

Application February 16, 1938, Serial No. 190,690

9 Claims. (Cl. 128—76.5)

The invention relates to apparatus for orthoptic training and development of the extrinsic eye muscles.

An object of the present invention is to provide an eye muscle exercising apparatus of the character described, having a pair of fixation targets and means for providing separated monocular vision of these targets and means for causing the movement of targets through predetermined paths for imparting desired motor nerve impulses to the eye muscles.

Another object of the invention is to provide a controlled, smooth moving, target support and drive means for progressively changing the spacing between the targets for producing a prismatic stimulation of the eye muscles while the targets themselves are caused to move through a closed rotary path. In accordance with the present construction the targets may be so arranged and regulated that they may be moved through smooth rhythmic paths from the weakest prismatic position to the strongest prismatic position without causing a condition of diplopia to take place and to alternately stress and relieve certain of the extrinsic eye muscles to be treated.

A further object of the invention is to provide an eye muscle exercising apparatus of the character above, wherein the target paths may be adjusted for combined exercise and stimulation of the superior and inferior oblique extrinsic eye muscles associated with the extrinsic recti muscles while maintaining single binocular vision.

Still another object of the invention is to provide an apparatus of the character above, wherein the targets may be initially positioned and thereafter caused to move through appropriate paths for stimulating abduction, adduction, infra-duction and supra-duction while maintaining binocular vision and fusion or stereopsis.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings:

Figure 1 is a perspective view of an eye muscle exercising apparatus constructed in accordance with the present invention.

Figure 2 is a fragmentary plan sectional view of the apparatus.

Figures 3, 4, 5 and 6 are diagrammatic representations of various target movements provided by the present apparatus.

Figure 7 is a front elevation of the target supporting stage.

Figure 8 is a rear elevation of the stage.

Figure 9 is a cross sectional view of the stage taken substantially on the plane of line 9—9 of Figure 8.

Figure 10 is an end elevation of the stage as indicated by the line 10—10 of Figure 8.

Figure 11 is a fragmentary cross sectional view of the stage taken substantially on the plane of line 11—11 of Figure 8.

Figure 12 is a horizontal cross sectional view of the stage taken substantially on the plane of line 12—12 of Figure 9.

Figure 13 is an enlarged fragmentary rear elevation of one of the driving connections for the targets.

Figure 14 is a horizontal cross sectional view of one of the control means taken substantially on the plane of line 14—14 of Figure 7.

Figure 15 is an enlarged rear elevation of the connection means of one of the targets to one of the drive means therefor.

The eye muscle exercising apparatus of the present invention and as illustrated in the accompanying drawings, consists briefly in a pair of fixation points or targets to be viewed by the patient, means for providing monocular vision of the targets to provide separate lines of sight thereon, and means for progressively diverging and converging said lines of sight and for otherwise displacing the same through a predetermined course of movement for producing a desired stimulation of the eye muscles. Preferably, the targets are initially adjusted laterally and vertically for compensating horizontal and vertical deficiencies in the extrinsic eye muscles while in maintaining binocular vision. In the preferred form of the invention the targets are caused to move generally through rhythmic rotary paths so as to not only impart the desired motor nerve impulses to the eye muscles but also to establish over their proper paths the reciprocal enervations as well. Coupled with the direct and reciprocal enervations caused by displacing the lines of sight around rotary rhythmic paths, the lines of sight are further caused to diverge or converge so as to produce a desired prismatic stimulation of the eye muscles while fusion or stereopsis is maintained.

The apparatus, as illustrated in Figure 1, comprises a casing or housing 11 having movably mounted on the front thereof a stage 12 supporting a pair of targets 13 and 14. The housing 11 is mounted on a base support 16 which has a forwardly extending arm 17 and carries a binocular eye piece 18 and an adjustable chin rest 19 for the user. Mounted between the eye piece and stage, to insure monocular vision of each of the targets, is a septum 21 which is preferably universally supported at its ends and provided with an expansion joint to enable movement of the targets and stage relative to the eyepiece. The eyepiece 18 preferably includes a pair of base-out spherio-prisms and may be arranged for use with base-in prisms or with plus or minus lenses for stimulation or relaxation of accommodation and convergence.

Preferably, the stage is supported by the casing 11 for movement through a rotary excursion, and is appropriately connected with drive and control means contained in the casing for driving the stage through such an excursion, and for adjusting the speed and amplitude of movement.

As here shown, the stage is in the form of a rectangular plate of metal or the like, and is supported for movement relative to the casing by means of a pair of cranks 22 and 23 having drive shafts 24 and 26 journaled in bearings 27 and 28 provided on the front wall 29 of the casing. The outer crank ends are provided with stub shafts 31 and 32 which are journaled in a pair of bosses 33 and 34 provided on a mounting bracket 36 secured to the back of the plate 12. As will be understood, the use of a pair of cranks of the character described for supporting and mounting the front plate affords a rotary displacement of the plate while maintaining the same in upright position with the targets in parallel relation to all positions of the rotary excursion. Means for driving the target may include any suitable source of power appropriately connected to the drive shafts 24 and 26 for rotating the cranks in unison and in a common direction of rotation. As here shown, the shafts 24 and 26 are provided with gears 37 and 38 which mesh with a drive pinion 39 connected by shaft 41 to a suitable source of power such as an electric motor or the like not shown.

As above mentioned, means is preferably provided for controlling the amplitude of movement of the stage and, as here shown, such control is afforded by arranging the cranks 22 and 23 for adjustment of the spacing of the eccentric shafts 31 and 32 relative to the central drive shafts 24 and 26. As will be seen in Figure 2, each of the cranks is constructed of two pivoted sections including an inner section 42 secured to the shafts 24 and 26 and an outer section 43 secured to the shafts 31 and 32. The sections are pivotally joined by means of a shaft 44 whereby the section 43 may be rotated relative to the section 42 for positioning of the shafts 31 and 32 at various distances from the shafts 24 and 26. Preferably, the pivotal connection 44 is spaced equidistantly between the shafts 24 and 31 and shafts 26 and 32, so that the shafts 31 and 32 may be positioned in coaxial alignment with the shafts 24 and 26 when no movement of the stage is desired.

Means for displacing the section 43 relative to the section 42 for adjusting the throw of the cranks is here provided in the form of gears 46 and 47, the former being mounted on sleeves 48 surrounding shafts 24 and 26 and the latter being mounted on the pivot shaft 44. Mounted on

the inner ends of the sleeves 48 are gears 49 which are connected to an intermediate pinion mounted on a control shaft leading to an exterior portion of the casing not shown.

The general assembly so far described, including the stage and targets and movable support therefor, is of the general design disclosed in United States Patent No. 2,091,173 to Wottring. This latter patent discloses in detail a drive and supporting means for the stage, including means for adjusting the speed and amplitude of movement of the stage, means for controlling the luminosity of the targets, means for starting and stopping and reversing the stage movement, and other features which may be used in connection with the present device.

In accordance with the present invention, I provide, in combination with an apparatus of the type described, means for uniformly and progressively diverging or converging the monocular lines of sight during the rotary or other excursion of the stage, so as to produce a prismatic stimulation of the extrinsic eye muscles from a weak to a strong prismatic strength without causing diplopia. This divergence and convergence of the lines of sight is preferably effected along horizontal or oblique linear paths so that the actual or apparent movement of the targets is a combined rotary and linear displacement. As will be understood, the divergence or convergence of the lines of sight may be effected optically by means of suitable prisms or other optical devices, or by displacing the targets themselves. In the preferred form of the invention, as here illustrated, the latter means is used, and the targets are mounted for movement relative to the stage and are driven during the rotary excursion of the stage to progressively change the spacing between the targets, either horizontally or obliquely. This change in spacing of the targets is preferably effected slowly and progressively during movement of the stage, so that the movement of the targets is scarcely detectable or noticed by the eyes until the act of diplopia takes place. In this manner, much greater prismatic stimulation may be produced than under a more rapid or less uniform change in spacing between the targets. Also in this regard, the attraction of the eyes around substantially closed rhythmic rotary paths greatly facilitates the change in spacing of the targets without loss of fusion or stereopsis.

In accordance with the present construction, the targets 13 and 14 are mounted on the front plate 12 for transverse reciprocation across the 55 plate and preferably displaced by a suitable driving connection connected to the driving connection for the stage so that the change in spacing between the targets may be positively and uniformly effected simultaneously with the rotary excursion of the stage. As here shown, the targets comprise a vehicle or carrier frame 51 which extends vertically across the face of the plate 12, around the top and bottom edges 52 and 53 thereof to the rear side of the plate so 65 as to securely hold the targets against removal from the plate and, at the same time, permit transverse or horizontal movement of the targets on the plate. In order to facilitate transverse displacement of the targets on the plate, the rear 70 upper ends 52 and 53 of the target carrier frames are connected to slide blocks 54 and 56 which are preferably engaged with guide strips 57 and 58 at the rear side of the plate 12, the strips being here formed with longitudinal grooves for re- 75

ceipt of interfitting portions on the slide blocks. In the present device the targets are displaced by means of a drive cable 59 which is carried on the rear side of the plate around a cable 5 drum 61 mounted adjacent one end 62 of the plate, and extends from the drum over rollers 63 and 64 adjacent and above the drum 61 transversely across the plate into substantially parallel legs 66 and 67 to adjacent the opposite end 68 of the plate where the cable is supported by a sheave 69. The legs 66 and 67 of the cable pass through parallel grooves 71 and 72 in the slide block 54 and grooves 73 and 74 in the slide block 56. Means is preferably carried by each 10 of the slide blocks 54 and 56 for detachably connecting the same to the cable and, as here shown, the block 54 is provided with a cam lock in the form of a roller 76 adjacent the groove 72, and which is provided with an eccentric groove 15 77 over a part of this circumference which may be moved into registration with the groove 72 to permit free passage of the cable leg 67 through the groove 72. The size and positioning of the roller 76 is such, however, that upon the rotation 20 of the same to remove the groove 77 out of registration with the groove 72, a portion of the periphery of the roller will bind the cord against one side of the groove 72 so as to lock the slide block 54 to the cable leg 67. The cam 25 roller 76 is preferably provided with a laterally extending arm 78 which extends vertically through a cutout portion 79 in the block to permit manual engagement and displacement thereof above the top 52 of the plate. A similar cam locking means 81 is provided on the slide block 30 56 in association with the groove 73 for releasably locking the block to the cable leg 66. Preferably, the guide members 57 and 58 are suitably arranged adjacent their opposite ends to 35 prevent longitudinal movement of the slide blocks 54 and 56 therefrom. This may be effected by the provision of any suitable stop means at the ends of the members 57 and 58, such as here shown by closing the ends of the guide grooves 40 provided by the members. Preferably, the ends of the cable are suitably fixed to the drum 61, such as here shown by means of a pin 81 so as to cause a positive movement of the cable with the drum.

45 In accordance with the above arrangement of the targets and drive therefor, the movement of the targets is effected by a slow reciprocal oscillation of the drum 61 during the movement of the stage so as to cause a corresponding slow reciprocal movement of the cable legs 66 and 67 and the targets connected thereto. As aforementioned, the drive for the targets is obtained from the drive for the stage and as here shown, one of the outer crank shafts 32 is provided with 50 a pinion 82 which meshes with a gear 83 carried on the rear side of the plate 12, whereby upon rotation of the crank 23 a relative rotation of the gear 83 and the stage will be established. The gear 83 meshes with an idler gear 84 which is in turn meshed with a pitman gear 86 for driving the cable drum. The connection 55 between the gear 83 and the drum is here effected by means of a link 87 pivoted eccentrically at one end 88 to the cable drum adjacent the periphery thereof and being similarly pivoted eccentrically at its opposite end 89 to the gear 86, whereby rotation of the latter will cause a reciprocal oscillation of the drum.

60 As an important feature of the present invention, means is provided for controlling the amplitude of movement of the targets relative to the stage, so that any degree of prismatic stimulation may be effected. The adjustment of the target movement is here provided by means of an adjustment of the eccentricity of the pivoted 5 end 89 of the link relative to the gear 86. In the present structure, the link end 89 is pivoted to an eccentric 91, as by means of a pin 90, carried by the gear 86 and which is provided with a mounting shaft 92 journalled in the gear and 10 extending therethrough to the front side of the plate 12. Preferably, the gear itself is provided with an enlarged hub portion 93 which extends through the plate and is journalled in bearing ring 94 in the plate and the eccentric shaft 92 15 is extended through the hub portion 93. As will be seen from Figure 8, the axis of the shaft 92 may be arranged equidistantly from the pivotal point 90 of the link end 89 and the axis of rotation of the gear 86, so that upon rotation of 20 the eccentric 91 the pivot 90 may be moved from a position in coaxial alignment with the axis of the gear to a rotated position substantially 180° therefrom with the pivot in its greatest eccentric position on the gear. In the first mentioned 25 position it will be understood that no relative movement of the cable drum will be effected upon rotation of the gear 86, whereas in the last mentioned position a maximum displacement of the cable drum will be effected. Between 30 these two rotated positions of the eccentric substantially any desired movement of the cable drum and the targets may be provided. Preferably, a manual control knob 95 is provided on the outer end of the shaft 92 for indicating the 35 position of the eccentric 91 relative to the gear 86. If desired and as here shown, releasable lock means may be provided between the knob 95 and the front exposed surface 97 of the gear hub 93, such as a spring pressed ball 98 carried by the 40 knob and which is engageable in a plurality of circular spaced sockets 99 on the hub surface 97. Preferably, the sockets 99 are arranged around substantially 180° relative to the axis of the knob so as to afford a complete adjustment 45 of the throw of the eccentric.

46 It will now be understood that upon setting of the eccentric 91 at some position of eccentricity to the gear 86, a reciprocal movement of the cable drum will be effected during the rotary excursion 50 of the stage, so as to slowly and uniformly and progressively increase and decrease the target spacing during such excursion. In accordance with the present invention and as a further important feature thereof, I provide for the widening or narrowing of the target spacing along controlled linear paths either horizontally or obliquely to the stage so that special exercises may be used for both the recti as well as the superior and inferior oblique extrinsic eye muscles. This 55 is here effected by the use of a pair of tracks 101 and 102 which are pivoted to the front side of the plate 12 as by means of a hub portion 103 which is extended through an opening 104 in the plate and the rear side thereof is held 60 in adjusted rotated position by means of a spring 106 compressed between a friction washer 107 and a nut 108 carried by the rear end of the portion 103. The forward face of each of the tracks 101 and 102 is provided with a longitudinal guide groove 109 which is arranged to receive a lug portion 111 of an outer movable target member 112, the lug 111 being here extended through a vertical elongated slot 113 in the rear target vehicle or carrier 51. In this manner the 70 75

tracks 101 and 102 may be adjusted about their pivotal connection to the frame, so as to arrange the longitudinal tracks 109 at any desired incline relative to the plate 12, and upon traverse movement of the targets across the plate the targets will follow the linear path defined by the grooves 109. Preferably, the target member 112 is arranged to removably carry various target images for attracting the eye and as here shown, the upper and lower ends 114 and 116 of the member are folded to define a pair of transverse tracks for receipt of cards or other indicia bearing members. The tracks 101 and 102 may also be used to initially adjust the vertical position of the targets on the stage when the latter are not positioned directly over the axis of rotation of the tracks, by properly rotating the tracks. Preferably, the target members 51 are provided with a vertical calibrated scale for indicating vertical imbalances of the eyes, the numerical values of the scale being readable at the upper and lower ends 114 and 116 of the target member 112. Similarly, scales 117 and 118 are preferably provided along the upper edge of the stage 12 for cooperating with pointers 119 and 121 carried by the target members 51 for indicating horizontal imbalances of the eyes.

The operation of the present apparatus as set forth above, may be summarized as follows: The patient is first carefully examined to determine imbalances existing in the extrinsic eye muscles and the amount of such imbalances. From such tests appropriate exercises for the various extrinsic eye muscles are determined and the apparatus adjusted accordingly. Normally, some rotary excursion of the stage is desirable and the amplitude of such excursion may be set by adjusting the eccentricity of the cranks 22 and 23. Likewise, the speed of the rotary excursion may also be adjusted by a suitable speed governor or rheostat or the like, such as described in the Wottring patent above referred to. The degree of prismatic stimulation desired is then adjusted by setting the knob 96 to cause a progressive change in spacing of the targets during the aforesaid rotary excursion of the stage. Initially, the targets may be set at any position relative to the horizontal scales 117 or 118 by moving arms 78 to release the targets from the cable drive therefor. The targets may then be caused to move progressively inwardly or outwardly from an initially set position by merely moving the arms 78 to connect the targets to the cable drive at the proper position of the cable drum. This may be readily determined by leaving the targets connected to the cable and moving the same to their end position, and then disconnecting the targets from the cable and moving them to any desired initial position. After the amplitude of rotary excursion has been adjusted and the amplitude of prismatic separation of the targets has been set, the tracks 109 may be adjusted to cause the targets to move relative to the stage along linear paths either horizontally or obliquely disposed relative to the stage. When both the rotary excursion and prismatic movements are used, the targets will follow a locus defined by the combined rotary and linear displacements. Two such target movements have been illustrated in Figures 3 and 4. In Figure 3 the tracks are set horizontally relative to the stage and the targets move along cycloidal paths away from each other, as indicated in dotted lines, and by the successive positions of the circles A, B and C. After the targets have thus

separated by a predetermined distance determined by the adjustment of the knob 96, the targets will move inwardly through the complimentary cycloidal paths to the initial position indicated at A. In Figure 4, the locus of the targets has been illustrated where the tracks are set in inclined position. As here shown, the targets again move through cycloidal paths generated by the rotary movement of the stage and the linear displacement along the tracks indicated by lines 122 and 123. In this figure the successive positions of the targets are illustrated by circles A, B, C and D, and as in the case above described, the targets will separate to an end position of separation and then return to an initial position. The two target movements illustrated in Figures 3 and 4 are given for the purposes of illustration, it being obvious that substantially any combination of linear and rotary movement is possible by proper adjustment of the apparatus. Also it is possible with my apparatus to produce a pure rotary excursion of the stage and targets without any prismatic movement, by merely setting the knob 96 to position the axis of pivot 90 in alignment with the axis of gear 86, as described in the foregoing. Also, the apparatus may be adjusted to produce a simple prismatic stimulation without any rotary displacement of the targets by adjusting the cranks 22 and 23 to a zero position of rotation and setting the knob 96 on any desired prismatic movement of the targets. Two such movements are shown in Figures 5 and 6, the movement in Figure 5 representing a pure linear movement with the tracks set in horizontal position and the movement in Figure 6 with the tracks in oblique positions.

I claim:

1. An apparatus for exercising the extrinsic eye muscles comprising, a fixed casing, a pair of movable crank arms carried by said casing, a stage connected to said crank arms and movable therewith, a pair of targets supported by and movable on said stage, means providing monocular vision of said targets, drive means for displacing said crank arms through a predetermined movement, and drive means carried by said stage and connected to said crank arms for progressively changing the spacing between said targets during said movement along lines changing the convergence and divergence of the monocular lines of sight provided by said first means.

2. An apparatus for exercising the extrinsic eye muscles comprising, a fixed casing, a pair of crank arms adapted to be moved in a predetermined path, a stage carried by and movable with said arms, a pair of targets supported by and movable on said stage, means providing monocular vision of said targets, drive mechanism for displacing said arms and stage through said predetermined path, and a gear train connected to one of said crank arms and to said targets for progressively changing the spacing of said targets during the course of said movement along lines changing the convergence of the monocular lines of sight provided by said first means.

3. An apparatus for exercising the extrinsic eye muscles comprising, a stage, a pair of targets movably supported on said stage, means providing monocular vision of said targets, means for moving said stage through a closed rotary path, means for simultaneously displacing said targets relative to said stage, tracks carried by said stage and engaged with said targets for confining the

movement of said targets relative to said stage along linear paths, said tracks being mounted on said stage to permit change of inclination of said tracks relative to a horizontal position thereof on said stage.

4. An apparatus for exercising the extrinsic eye muscles comprising, a fixed casing, a crank arm carried by said casing, a stage carried by and movable with said arm, a pair of targets movably supported by said stage, means providing monocular vision of said targets, drive means carried by said casing for displacing said arm and stage through a closed rotary path, a crank rotatably carried by said stage, and means connected to said drive means and crank for imparting a rotary motion to the latter, said crank being connected to said targets for progressively changing the spacing between said targets on said stage during said movement.
5. An apparatus for exercising the extrinsic eye muscles comprising, a fixed casing, a stage, a pair of targets movably supported by said stage, means providing monocular vision of said targets, a crank rotatably carried by said body and connected to said stage for displacing said stage through a closed rotary path, a second crank carried by said stage, and means carried by said stage and connected to said first and second cranks to rotate said second crank from the motion of said first crank, said second crank being connected to said targets for progressively changing the spacing between said targets during said movement, and said second crank having an adjustable throw for regulating the amount of change in spacing of said targets during said movement.
6. An apparatus for exercising the extrinsic eye muscles comprising, a support, a relatively movable front plate, drive means, an eccentric driven by said means and connected to said plate for displacing the latter through a rotary path, a crank carried by said plate and geared to said eccentric, a pair of targets movably carried by said plate, means for producing monocular vision of said targets, and drive means connect-

ing said crank and targets for progressively changing the spacing of the latter during movement through said path with said plate.

7. An apparatus for exercising the extrinsic eye muscles comprising, a relatively movable front plate, drive means, an eccentric driven by said means and connected to said plate for displacing the latter through a rotary path, a crank carried by said plate and geared to said eccentric, a pair of targets movably carried by said plate, means for producing monocular vision of said targets, drive means connecting said crank and targets for progressively changing the spacing of the latter during movement through said path with said plate and means for detachably connecting said targets with said last named drive means.

8. An apparatus for exercising the extrinsic eye muscles comprising, a support, a relatively movable front plate, drive means, an eccentric driven by said means and connected to said plate for displacing the latter through a rotary path, a crank carried by said plate and geared to said eccentric, a pair of targets movably carried by said plate, means for producing monocular vision of said targets, a drum carried by said plate and oscillated by said crank, a cable driven by said drum, and means carried by said targets for detachably connecting the same to said cable.

9. An apparatus for exercising the extrinsic eye muscles comprising, a support, a relatively movable front plate, drive means, an eccentric driven by said means and connected to said plate for displacing the latter through a rotary path, a crank carried by said plate and geared to said eccentric, a pair of targets movably carried by said plate, means for producing monocular vision of said targets, a drum carried by said plate and oscillated by said crank, a cable driven by said drum, means carried by said targets for detachably connecting the same to said cable, and means engageable in the front of said plate for adjusting the throw of said crank.

PHILLIP S. NEWTON. 45
